AUXILIARY BED CONTROLLED SWITCH
FOR ELECTRIC ALARM CLOCKS

Daniel E. Belich, West Allis, Wis.

Application December 8, 1945, Serial No. 633,681

8 Claims. (Cl. 161—22)

1

My invention relates to improvements in automatic alarm mechanism.

The primary object of my invention is to provide a clock or other timing device with a low voltage alarm circuit having time controlled means for closing the circuit at one point, and auxiliary means for utilizing the weight of the occupant of a bed to automatically close the circuit at another point, whereby an alarm will be sounded at the proper time if the bed is occupied, but not otherwise.

A further object is to provide an electric alarm clock operable on a relatively high voltage circuit, with alarm mechanism automatically operable on a low voltage circuit, controlled in part by the clock mechanism and in part by the weight of a person in the bed.

A further object is to provide means for utilizing the low voltage circuit to continuously sound an alarm for a prolonged period of time unless the circuit is automatically broken by relieving the bed of the weight of the occupant.

A further object is to provide inexpensive means for modifying an ordinary electric clock in such a manner as to eliminate its electro-magnetic means for operating an alarm bell and substitute therefor low voltage electrical means for operating an alarm, subject to dual control by the clock mechanism and the weight of a person occupying the bed.

Further objects will be apparent from the description of the embodiment of my invention disclosed in the drawings.

In the drawings:

Figure 1 is a perspective view of a bed and an associated electric alarm clock embodying my invention.

Figure 2 is a plan diagram of the alarm clock mechanism, showing an associated suspensory switch in vertical section.

Figure 3 is a detail view of the mechanism for closing the alarm circuit at a point within the clock casing.

Figure 4 is a detail view of the means for closing the alarm circuit by contact of the bed controlled switch with the floor underneath the bed.

Like parts are identified by the same reference characters throughout the several views.

The clock casing 10 contains an electric clock 11 of ordinary type operable on a 110 volt circuit supplied through any ordinary outlet when its conducting wires are plugged in, as indicated at 12 in Figure 1. Ordinarily such clocks are provided with an electro-magnetically operable

2

bell, in said circuit, but I have substituted therefor, a low voltage electric buzzer or bell 14, the operation of which is time-controlled in part by means associated with the hour hand of the clock, and also controlled in part by a pendant switch 15 supported from a bed spring 16 in a normal circuit breaking position. This switch is so constructed that when brought into contact with the floor it will be automatically adjusted to circuit closing position, and its normal proximity to the floor is such that even the weight of a small person on the bed spring will depress it sufficiently to allow the switch to contact the floor and close the circuit. Switch 15 is connected with the bed spring by the cord 17 and a metal hook 18 engageable with one of the wires 19 of a bed spring at any desired point.

As shown in Figure 2, the switch 15 has two terminals 20 and 21 mounted in a block 22 of insulating material. A conducting bar or plate 24 mounted on supporting insulation 25 in a cup-shaped member or receptacle 26 is loosely suspended from the insulating block 22 by studs 27 slidingly engaged in grooves 28 formed in said block. The member 26 is normally held by gravity with its studs 27 at the lower ends of the grooves 28. But when the bed spring is depressed sufficiently, the member 26 may contact with the floor and continued downward movement of the spring will allow the block 15 to continue to descend until the terminals 20 and 21 contact the plate or bar 24, thus closing at this point the low-voltage circuit now to be described and which includes the bell, buzzer 14, chimes, or other alarm.

A transformer 30 has its primary connected with the leading in wires 31 and 32 of the clock 11. Wire 31 is connected by tap wire 33 with the primary side of the transformer at 34. The return circuit of the transformer primary is through wire 36, cut out switch 37, flasher or interrupter 38 and wire 39 to wire 32 of the clock circuit.

The secondary of the transformer delivers current, preferably at six volts, through wire 40 to terminal 20 and through switch plate 24, terminal 21, and wire 41 to the bell or buzzer 14, thence through wire 42 to a terminal 43 mounted on the clock frame with interposed insulation at 44. This terminal may be contacted by a yoke-shaped switch member 46 journaled at 47 in supporting brackets 48 and urged by torsion spring 49 to the right in Figure 3. The switch 46 carries a boss 50 which contacts the hub 51 of a slidable clock-driven timing gear wheel 52

which is rotated by the clock mechanism once every 12 hours, i. e. in accordance with the movement of the hour hand. The timing gear wheel 52 is mounted to slide on a shaft 53 which also supports a setting wheel 55 having teeth in mesh with a pinion 56 on a manually rotatable shaft 51 provided with an operating knob 58.

The timing gear wheel has on its inner face an arcuate spacing projection 60 which normally bears on the outer face of the setting wheel 55 but is adapted to enter the setting wheel slot 62 once in every 12 hours, and temporarily allow the switch 46 to swing to the right in Figure 3 thereby closing the low-voltage circuit at 65 through the wire 66, rheostat 67 and wire 68.

If the low-voltage circuit is also closed by the switch plate 24 underneath the bed an alarm will be sounded by the buzzer or bell 14. It will continue to sound as long as both switches are closed, but will cease to sound as soon as the bed is relieved of the weight of the occupant. If the bed spring does not withdraw the terminals 20 and 21 from the plate 24, the alarm will continue to sound until the rotation of the timing gear 52 withdraws its spacing projection 60 from the slot 62 in the setting wheel 55, thereby pushing yoke-shaped switch 46 to circuit breaking position.

It is not necessary that the bed spring should withdraw cup-shaped member 26 from the floor, or from any other fixed support upon which it may rest underneath the bed, the circuit being broken merely by withdrawal of the terminals 20 and 21 from the plate 24. In the construction shown, the insulating block 22 is threaded into a metal cap 23, having an aperture through which the cord 17 is passed, and provided with a retaining knot 17.

Any suitable timing switch mechanism may be substituted for that disclosed in Figure 3. Various kinds of timing switch mechanisms are common in the art, and it will be obvious to those skilled in the art that it is immaterial which one of these timing switches is employed to connect up the low-voltage circuit within a clock at the proper time as determined by the adjustment of the manually operable setting shaft 57.

The specific structure of the weight-controlled switch underneath the bed is also subject to considerable variation from that illustrated in the drawings, as will be readily understood by those skilled in this art, and while I prefer to use an electric clock which can be plugged into any ordinary light circuit and operated on the voltage thereof, any other clock may be employed, and the transformer may have its primary separately plugged into a lighting circuit and its secondary connected with timing mechanism operatively connected with the clock, since both the timing switch and the weight-operated switch associated with the bed are included in a low-voltage circuit which may or may not be associated with a clock operating circuit. The use of switches and flexible cords more or less exposed makes it desirable to use a low-voltage circuit which will not impose any fire hazards on the assembly or the building in which it is installed.

I claim:

1. The combination with a timing device, of a transformer, electrically operable means for sounding an alarm included in the secondary circuit of the transformer, time controlled means associated with the timing device for connecting up the alarm circuit at one point, and means associated with a bed spring for connecting up said circuit at another point when the bed spring is

depressed, said last mentioned means including a normally open electric switch suspended from the bed spring in proximity to a relatively stationary object below the bed, said switch being adapted to be closed by pressure contact with said object.

2. The combination with an electric clock provided with means for connecting it with a lighting circuit outlet, of a transformer installed in the clock casing, alarm mechanism also installed in said casing and operatively connected with the secondary of the transformer, and a set of switches connected in series in the secondary circuit of the transformer, one of said switches being operable by the clock mechanism and the other comprising a weight operable switch provided with a hook for its support from a bed spring in a pendent position therebeneath, said weight-operable switch including a movable contact and a downwardly disposed actuator adapted to contact the floor beneath the bed spring when the bed spring is depressed, whereby to close the weight-operable switch.

3. In a device for operating a clock-controlled alarm only when a bed spring is depressed, said device comprising the combination with an electric clock provided with means for connecting it with a lighting circuit outlet, of a transformer installed in the clock casing, alarm mechanism also installed in said casing and operatively connected with the secondary of the transformer, and a set of switches connected in series in the secondary circuit of the transformer, one of said switches being operable by the clock mechanism and the other comprising a weight operable switch associated with the bed spring and suspended therefrom in proximity to the floor underneath the bed.

4. The combination in an electrical alarm circuit, of normally open switches connected in series and the closing of both of which being requisite to the functioning of such circuit, one of said switches comprising a circuit closer and a clockwork actuator therefor, and the other of said switches comprising a pair of relatively movable contacts, one of which is provided with means for its suspension beneath a bed spring and the other of which is adapted to receive motion from the floor beneath the bed spring when the bed spring is occupied.

5. In a device of the character described, the combination with an electrical alarm, of a circuit for the operation thereof including a pair of switches in series in such circuit, each of said switches comprising normally open contacts, a clockwork mechanism operatively connected with a contact of one of said switches for the closing thereof, the other of said switches being provided with a hook for its suspension and with a downwardly disposed switch closing actuator.

6. In a device for rendering an alarm circuit operative at the time for which the alarm is set only when a bed is occupied at such time, the combination with an electrical alarm and a circuit for the operation thereof including a source of energy, of a pair of switches connected in series with said circuit, a time clock adjustably connected with one of said switches for the closing thereof at a selected hour, the other switch comprising a pair of contacts, a dielectric support in which said contacts are mounted, a hook for suspending the dielectric support and contacts from the bed bottom, and a circuit closer movable with respect to the dielectric member and normally in circuit opening position, the position

of said hook respecting the circuit closer being such that the circuit closer will normally be supported clear of the floor beneath the bed bottom save when the bed is occupied and will engage such floor to close said last mentioned switch contacts when the bed is occupied.

7. In a time-controlled electric alarm mechanism, a switch in the circuit of said mechanism and comprising normally open contacts in combination with a tension support comprising a hook for detachably suspending the switch from a bed spring in proximity to a relatively fixed switch operating member, one of the contacts of said switch being mounted for movement to and from the other contact thereof and downwardly disposed in position for closing said fixed switch when the bed spring is depressed.

8. A low voltage alarm circuit having a controlling switch comprising a gravity actuated

member provided with terminals, a circuit closing member movably suspended below the terminals and downwardly disposed for circuit closing movement with respect to said terminals when the terminals are depressed below a predetermined normal position, and a member for suspending the circuit closing member.
